Application October 25, 1949, Serial No. 5,703

Term of patent 7 years

(Cl. D3—17)

To all whom it may concern:

Be it known that I, Sydell Sinsley, a citizen of the United States, and a resident of Miami, Dade County, Florida, have invented a new, original, and ornamental Design for Panties, of which the following is a specification, reference being had to the accompanying drawing, forming part thereof wherein

Fig. 1 is a front view of a pair of panties showing my new design,

Fig. 2 is a rear view, and

Fig. 3 is a side view thereof.

The characteristic feature of my design resides in the combination on the panties disclosed of the specific three rows of ruffles which are gathered at their point of attachment and edged with contrasting lace together with a pair of bows overlying the bows on the top ruffles, all as shown.

I claim:

The ornamental design for panties, as shown and described.

SYDELL SINSLEY.
